(57) **CLAIM**

The ornamental design for a closure for can, as shown and described.

DESCRIPTION

FIG. 1 is a perspective view of a first embodiment of a closure for can;

FIG. 2 is a perspective view of the first embodiment shown in FIG. 1, rotated 90 degrees;

FIG. 3 is a side view of the embodiment shown in FIG. 1, with the opposite sides being a mirror image thereof;

FIG. 4 is a top plan view of the embodiments shown in FIG. 1 and FIG. 2;

FIG. 5 is a bottom plan view of the embodiments shown in FIG. 1 and FIG. 2;

FIG. 6 is a perspective view of a second embodiment of a closure for can;

FIG. 7 is a perspective view of the second embodiment shown in FIG. 6, rotated 90 degrees;

FIG. 8 is a side view of the embodiment shown in FIG. 6, with the opposite sides being a mirror image thereof;

FIG. 9 is a top plan view of the embodiments shown in FIG. 6 and FIG. 7;

FIG. 10 is a bottom plan view of the embodiments shown in FIG. 6 and FIG. 7;

FIG. 11 is a perspective view of the third embodiment of a closure for can;

FIG. 12 is a perspective view of the embodiment shown in FIG. 11, rotated 90 degrees;

FIG. 13 is a side view of the embodiment shown in FIG. 11 and FIG. 12, with the opposite side being a mirror image thereof;

FIG. 14 is a top plan view of the embodiments shown in FIG. 11 and FIG. 12; and,

FIG. 15 is a bottom plan view of the embodiments shown in FIG. 11 and FIG. 12.

All broken lines in the drawings depict unclaimed environmental subject matter only and form no part of the claimed design.
